UNITED STATES PATENT OFFICE.

ALBERT E. MOORE, OF SEATTLE, WASHINGTON.

STAIN-REMOVING COMPOUND.

No Drawing.

Application filed July 16, 1925. Serial No. 44,114.

To all whom it may concern:

Be it known that I, ALBERT E. MOORE, a citizen of the United States of America, and resident of the city of Seattle, in the 5 county of King and State of Washington, have invented certain new and useful Improvements in Stain-Removing Compounds, of which the following is a specification.

My invention relates to a detergent compound 10 intended for use to remove stains caused by fruit and vegetable juices from the skin, particularly from the hands.

In particular my invention is designed as a compound for the use of florists and 15 gardeners, to remove from their hands the loose dirt, but more especially to remove the stains received in the handling of plants and cut flowers. It is also useful in the kitchen to remove from the hands the stains 20 caused through handling, paring, and otherwise preparing fruits and vegetables, as potatoes, tomatoes, peaches, and berries, for example.

My invention comprises the compound 25 hereinafter set forth and claimed, and in substantially the proportions stated, although it will be understood that the proportions are capable of substantial variations, although perhaps with lessening of 30 the efficiency and intensity of the compound as the proportions are more widely varied from those which are the preferred proportions.

The ingredients included in the present 35 compound are as follows, the proportions given being by weight:—Citric acid, 45%; pumice stone, 45%; cuttle-fish bone, 10%; satchet powder, essential perfume oils, or like scenting substances, a very small 40 amount.

The three essential ingredients, the citric acid, pumice stone and cuttle-fish bone, are taken in powdered form and are mixed together in this form to provide a powder, 45 which when added to water and worked up on the hands will form a lather which penetrates the cracks and crevices of the hand, and thus by its combined mechanical and 50 chemical action removes the loose dirt and the stains. The citric acid appears to act chemically upon the stains to permit their removal, while the pumice stone appears to act mechanically to remove the constituents of the stains thus attacked and to remove 55 the loose dirt; the cuttle-fish bone acts as a binder to hold the other two ingredients

together to form a lather and thus to introduce the other two ingredients into the cracks and crevices of the hands so that they may act directly upon the stains and 60 dirt.

The citric acid employed may be a commercial grade, not necessarily chemically pure, and as stated above, in powdered form. The pumice I prefer to use is of a grade 65 known to the trade as 3-F, which is the finest grade supplied commercially, although coarser grades may be used. The finer the pumice stone the more readily it will penetrate the small crevices and the less 70 harsh will be its effect on the skin. The cuttle-fish bone, as explained above, is supplied in powdered form. The scenting ingredient is, of course, not essential, but its use is preferable in order to leave the hands 75 pleasingly scented. If satchet powder or a like powdered scent is employed this may be added in the powdered form when mixing the other three ingredients. If oils are employed these may be added to the ground 80 pumice stone, which is then dried and again powdered.

The compound so formed will readily and quickly remove from the hands, etc., stains of the class described. It will not, however, 85 attack grease, and for that reason should not be used as a substitute for soap; rather it is to be used as an aid to soap, the soap removing the greases and the greater proportion of the surface dirt, and the present compound removing the stains and the dirt 90 which has been ground in. The present compound is altogether harmless to the texture of the skin.

The present compound can be used as a 95 base for a paste and for this purpose may be mixed with water. It is not preferred to make such a paste with it except for immediate use, as the citric acid apparently is affected by the water and appears to lose 100 its strength if so mixed and kept for any considerable period. It will not mix readily with oils, glycerine, soap, or any greasy material. Preferably it is made and used as a powder, a small amount being taken on 105 the hands, moistened, and then rubbed over the entire surface. It is not intended to be used to remove stains from cloth, although it will remove the same stains, as fruit juices, for example, from the hands.

As has been noted, the proportions given above are preferred, but any one of these

can be varied five per cent in either direction without materially affecting the action of the compound. Further variation of the proportions, however, will so materially lessen the effect of the compound by making it slower to act, that such further variation is not desirable. However, it will be evident that where this is not a material drawback, the proportions may be widely varied from those given above, and still approximate results obtained in that manner.

What I claim as my invention is:

1. A compound for the purpose specified,

comprising the following ingredients in substantially the proportions, as follows:—¹⁵
Powdered citric acid, 40-50%; powdered pumice stone, 40-50%; powdered cuttle-fish bone, 5-15%.

2. A compound for the purpose specified, comprising 45% of citric acid, 45% of ²⁰ finely ground pumice stone, and 10% of powdered cuttle-fish bone, mixed and in powdered form.

Signed at Seattle, King County, Washington this 10th day of July, 1925.

ALBERT E. MOORE.
